UNITED STATES PATENT OFFICE

2,458,314

VARIABLE ELECTRICAL RESISTOR

Eugene Leopold Straub, Wembley Hill, and Arthur Edward Charles Bennett, Kenton, England, assignors to Dubilier Condenser Company (1925) Limited, London England, a company of Great Britain

Application January 11, 1946, Serial No. 640,490
In Great Britain January 18, 1945

3 Claims. (Cl. 201—55)

1

This invention relates to variable electrical resistors and is more particularly concerned with small resistors, such as are commonly employed as volume controls in wireless receivers.

When such resistors are called upon to withstand frequent relatively large temperature cycles, and the combination of high temperatures and high humidity which are found in tropical climates, it is essential for them to be protected against the ingress of moisture and otherwise to be so constructed that the moving contacts and the cooperating resistance element will not be exposed to moisture. The main object of the present invention is to provide a simple and relatively cheap construction of hermetically sealed variable resistor which permits a standard resistor suitable for temperate climates to be used and does not entail special construction of the complete device.

The improved resistor according to the invention is hermetically sealed for operation under tropical conditions by enclosure in a metal casing having one closed end through which extends an adjusting spindle for the resistor whilst the other end of the casing is closed by a sealing disc of rubber or water-resisting rubber-like material, through which extend leads to the resistor, this end of the casing being hermetically sealed by resiliently pressing into the outer surface of the sealing disc both the edge of the casing and the flanges or rims of tubular rivets or eyelets fixed to the leads, so that the sealing disc is compressed and deformed to provide waterproof joints between the rubber and the metal pressed into it. Preferably the casing is cup-shaped and may, for example, be of aluminium, or other non-brittle metal.

This form of sealing is particularly applicable to so-called miniature construction and in the improved resistor according to the present invention, which enables the dimensions to be very considerably reduced as compared with normal construction, the resistor element is supported by the casing sealing disc whilst the adjusting spindle, carrying a moving contact for engaging the element, is carried by a bearing on the closed end of the casing so that the casing itself, which is cup-shaped, acts as the mechanical supporting structure of the resistor.

The invention may be carried into practice in various ways, but two convenient practical arrangements, each according to the invention, are shown by way of example and as applied to a volume control in the accompanying drawings, in which

2

Figure 1 shows one construction in side elevation,

Figure 2 is an exploded longitudinal section on the line II—II of Figure 4, but on a larger scale,

Figure 3 is a section on the line III—III of Figure 2,

Figure 4 is a section on the line IV—IV of Figure 2,

Figure 5 illustrates the resistor in end elevation from right to left of Figure 1,

Figure 6 is a diagrammatic representation of the electrical connections within the resistor casing,

Figure 7 is a fragmentary section through a modified form of sealing for the electric leads where they extend through the end discs,

Figure 8 illustrates a modified arrangement of the sealing rings between the adjusting spindle and its bearing,

Figure 9 is a view, similar to that of Figure 1, of a modified construction of resistor,

Figure 10 shows the resistor in end elevation from right to left of Figure 9,

Figure 11 is a view, similar to that of Figure 2, of the modified construction shown in Figures 9 and 10 but on a larger scale,

Figures 12, 13 and 14 are sections on the lines XII—XII, XIII—XIII and XIV—XIV of Figure 11 respectively,

Figure 15 is a diagrammatic representation of the electrical connections within the casing of the resistor shown in Figures 9 to 14 inclusive, and

Figures 16 and 17 illustrate two modified forms of tubular rivet which may be employed with either of the constructions above described.

In the construction shown in Figures 1 to 6 the resistor itself is of the usual type consisting of a disc A of rigid insulating material having on one surface a resistance element B consisting of a flat strip of conducting resistor material, such for example as a carbon compound, shaped as an annulus but with a break to provide two ends B₁, B₂ which are spaced from one another and are respectively connected through rivets B₃, B₄ to two terminal tags B₅, B₆ lying in recesses B₇ in the disc A. A moving contact C, consisting of several sprung fingers or wires, is resiliently pressed into contact with the strip B and is supported on an insulating contact arm C₁ carried at one end of a spindle D extending through a bore in the centre of the disc A. A main bearing for the spindle D consists of a metal boss E secured, by moulding-in as shown in Figure 2, to the disc A, the bearing E extending from the disc

55

on that side thereof remote from the strip B. The adjusting spindle D projects beyond the end of the bearing E and, when assembled, has an operating knob D₁ secured thereto. A sliding contact is provided between a metallic annulus C₂, carried by the contact arm C₁ and connected to the spring contact C through a metal strip anchored to the arm C₁ by a rivet C₃, and a bifurcated springy contact C₄ connected through a rivet C₅ to a third terminal tag C₆ lying in one of the recesses B₇ of the disc A. The spindle D is held in position in the bearing E, so that there is appropriate pressure between the contacts B, C and C₂, C₄, by a C washer D₂ which clips into an annular groove D₃ in the spindle D and thus forms a flange-like abutment bearing against the outer end of the bearing boss E. The outside of the bearing boss E is screwthreaded to receive a collar E₁ which is screwed on to the bearing boss E so as firmly to clamp the resistor unit within the metal casing F.

In order, in accordance with the invention, to make such resistor "trop'c-proof," it is enclosed in the metal casing F which is substantially cup-shaped and has a hole F₁ in its closed end through which projects the spindle D and a part of the bearing boss E. A thin annular ring G₁ of insulating material, for example of fibre, elephanthead or similar material, and of a diameter slightly less than the internal diameter of the casing F, is inserted in the casing before the resistor is assembled in the casing F and serves to prevent metallic contact between the casing F and any of the terminal tags B₅, B₆, C₆ on the main resistor disc A.

The joint between the edge of the hole F₁ in the end of the casing F and the bearing boss E is hermetically sealed. When the metal of the casing F and the boss E can readily be soldered, this seal can be effected by running solder around the edge of the hole F₁ after the resistor is in position. When, however, as is usual and preferable, the casing F is of aluminium, and thus cannot easily be soldered, the hermetic seal is provided by compressing, between the insulating disc G₁ and the inside of the end of the casing F, a washer G of rubber or a water-resisting rubber-like material, such for example as the synthetic rubber "neoprene." The rubber washer G is inserted on to the bearing boss E after the insulating disc G₁, and the casing F is countersunk to form a recess F₂ around the inside of the hole F₁ so that the washer G is trapped in the annular recess thereby preventing or reducing outward radial expansion of the washer when it is axially compressed. The washer G is compressed, so as to render the joint moisture-proof and water-proof, by the collar E₁ which, when tightened, draws the resistor towards the end of the casing F so that the washer G is compressed between the disc A and the said end of the casing. The radial inward expansion of the washer G as a result of this compression will cause the washer G to tighten on to the boss E, thereby assisting in the sealing against ingress of moisture.

An additional indentation F₆ is provided adjacent to the outer rim of the casing F and projecting outwardly to a greater extent than the recess or indentation F₂. The relative depths of the two indentations are preferably such that when the collar E₁ is clamped up tightly its outer face is approximately level with the outer indentation F₆. The outer end surface of the casing F of the complete resistor can thus be pressed against the surface of the panel (indicated at T)

on which it is mounted. A nut E₂ on the threaded boss E enables the user of the component to clamp it on to the panel T.

The disc A of the resistor unit itself with the interposed insulating washer G₁, bears against the annular surface F₇, being clamped thereto by the collar E₁. The insulating washer G₁ is preferably arranged to fit over the outside of the resilient washer G which thus bears directly against the more moisture impervious moulded disc A.

With a view to preventing accidental rotation of the resistor when it is mounted on a panel T, the casing F may be provided with an indentation F₈ which can co-operate with a pin or screw head secured in the panel T itself.

The open end F₃ of the casing F is sealed by a sealing disc H of rubber or of a waterproof rubber-like material such, for example, as "neoprene," which is supported by an inner or backing disc H₁ of rigid insulating material, such for example as the material sold under the registered trade-mark "Bakelite," the edge of the disc H₁ being engaged by an annular indentation or shoulder F₄ formed near the rim of the casing F by spinning or other suitable shaping operation. The hermetic seal is obtained by spinning over the rim F₅ of the casing F so that it presses into and deforms the outer surface of the rubber, or rubber-like, sealing disc H without perforating it.

The leads J, J₁, J₂ to the three terminal tags B₅, B₆, C₆ also extend through spaced holes in the discs H, H₁. Three tubular rivets K extend through the two discs H, H₁, the edges of the outer flanges of the rivets being pressed into the outer surface of the rubber disc H so as to deform it and thus form a water and moisture-proof joint as in the case of the joint F₅ at the rim of the casing F. The leads J, J₁, J₂ extend axially through the rivets K and are sealed therein by solder K₁ which also closes the bores of the rivets K. Alternatively, each lead J₃ (Figure 7) may have dished metal eyelets or washers K₂ soldered thereto after assembly, the edge of each outer washer K₂ being resiliently pressed into the outer surface of the disc H to effect the requisite seal.

In order that the bearing for the spindle D may also act as a sealing gland, the spindle is provided with an annular groove D₄ which, prior to assembly, is filled with a water-resistant oil or grease which serves also as a lubricant. In addition, the spindle D has formed therein two annular retaining grooves D₅ on opposite sides respectively of the groove D₄. Each groove D₅ has fitted therein a ring or washer D₆ of water-resistant rubber-like material, such, for example, as neoprene or hycar-or, the internal diameter of the ring D₆ being less than the diameter at the bottom of the associated groove D₅ whilst the external diameter of the ring is slightly greater than the internal diameter of the boss E. The rings D₆ are preferably of a synthetic rubber such for example as neoprene, or any other suitable rubber-like material possessing adequate oil resistance which will prevent deterioration by the oil or grease spreading over the surface of the spindle and its bearing from the groove D₄. Thus, on assembly, the resilient rings D₆ grip the spindle and are radially compressed between the spindle D and the bore of the bearing boss E and, though permitting free rotation of the spindle D, assist the action of the oil channel D₄ to prevent the ingress of moisture. Instead of the retaining grooves being formed in the spindle D, grooves D₇ (Figure 8) may be formed in the boss E in addition to the oil channel D₄ in the spindle

D, the external diameter of each resilient ring D₈ being greater than the diameter at the bottom of the associated groove D₇ whilst the internal diameter of the ring is slightly less than the diameter of the spindle D.

In order to limit the angular movement of the spindle D, and therefore the travel of the moving contact C over the resistor element B, an abutment A₁ formed integral with the disc A cooperates with a stud A₂ carried by the spindle D.

The construction above described particularly lends itself for mounting within the containers or casings of radio sets or other apparatus, which casings are sealed against ingress of moisture. To this end a ring of neoprene or other suitable material may be arranged in the recess F₇ (Figures 2 and 3) so that when the nut E₂ outside the casing is tightened the said ring is compressed and held against lateral expansion by the recess F₇. This ring thereby seals the opening in the casing through which the boss E extends.

In the modified construction shown in Figures 9 to 15, the dimensions may be very considerably reduced as compared with normal constructions of resistor or volume control, the resistor element L being supported by the rigid insulating backing disc M associated with the rubber, or rubber-like, sealing disc N. The adjusting spindle O, carrying the moving contact O₁ for bearing against the strip resistor element L, is journaled in a bearing boss P formed integral with the closed end wall R₁ of the metal casing R. Thus, the casing R itself, which is cup-shaped as shown in Figure 11, acts as the mechanical supporting structure for the resistor. With this construction the casing R and the boss P may be formed in two parts of brass, soldered together to form a hermetic seal, in which case they may conveniently be tin plated or cadmium plated to increase their resistance to corrosion by damp atmospheres. Alternatively, these two parts may be formed integrally together as for example by an extrusion process, in which case they may for example be constructed of hard aluminium, or aluminium alloy. As clearly shown in Figure 12, the strip-type resistor element L, formed as an annulus with a break in it, lies on, or in a recess in, the inner face of the rigid disc M which backs the rubber-like sealing disc N. The three leads Q₁, Q₂, Q extend into three tubular rivets Q₃, Q₄, Q₅ respectively, each rivet extending through the two discs M and N. The two rivets Q₃, Q₄ are electrically connected respectively to the two ends of the resistor element L and secure the resistor element to the rigid disc M (Figures 12 and 15), whilst the third rivet Q₅ is electrically connected to a bifurcated springy contact member whose two arms S carry contacts S₁ both of which bear against a metal plate O₂ lying on, or in a recess in, the outer surface of the insulating disc O₃ within which the adjusting spindle O is moulded. The moving contact O₁ is constituted by a tongue struck upwards from the plate O₂, as shown in Figure 13, the plate being secured to the disc O₃ by integral tongues O₄ on the plate O₂ extending through notches O₅ in the disc O₃ and being clinched over behind the disc, as shown in Figure 14. A stop R₂ formed within the casing R cooperates with a rib O₆ formed on the disc or block O₃ so as to limit the angular rotation of the spindle O and therefore the movement of the contact O₁ over the resistor element L.

The moving contact O₁ and the contacts S, S₁ may be of any suitable form to provide a good

and durable rubbing contact with the resistor element L and the plate O₂ respectively, but preferably these contacts are of stiff springy metal which may be plated with silver, nickel or other non-rusting metal, a cup or "pimple" being pressed out at or near the ends of each contact arm to provide a curved profile for engaging the cooperating surface L or O₂.

Alternatively the contact O₁ may be duplicate so as to provide a dual point of contact with the element L, a second tongue being struck upwards from the plate O₂ for this purpose so that the second contact lies closely adjacent to the first one. According to a further arrangement a multiple wire contact similar to that shown in Figure 2 and secured to the plate O₂ may be employed. Such multiple contacts are preferably arranged so that their points of contact with the resistor element L are made substantially on a radial line.

The seal at one end of the casing is effected as described with reference to Figure 2, that is to say by pressing the outer flanges of the rivets Q₃, Q₄, Q₅ into the outer surface of the rubber-like sealing disc N and then soldering the leads to close the outer ends of the rivets as indicated at Q₆. At the other end of the casing R, the boss P is externally screw-threaded to receive the clamping nut T₁ by which the resistor is locked to the panel T, whilst the adjusting spindle is held in position by a C washer T₂, as above described. Alternatively, the spindle O may be provided with a collar or the equivalent at its inner end which engages the inside of the casing R (or the insulating block O₃ may serve this purpose).

It will be appreciated that the dimensions of the various parts are such that when the end discs M and N are fitted on and the edge of the casing R spun over to effect hermetic sealing, the moving contact O₁ bears against the element L with the appropriate pressure whilst the contacts S₁ press against the plate O₂.

The bearing of the spindle O is sealed by means of the oil groove V and the two retaining grooves V₁ containing the compressible rings V₂, as described with reference to Figure 2, through the arrangement of Figure 8 may be employed.

Instead of the tubular rivets K or Q₃, Q₄, Q₅ described above each rivet may be formed with a tubular socket W (Figure 16) at its inner end for riveting over and soldering on to the associated lead within the casing, an intermediate integral rib W₁ being turned or pressed on the rivet for clinching over into the outer surface of the resilient sealing disc H or N. The outer end of the rivet has either a solder tag W₂, as shown in Figure 16, or a screwthreaded stub W₃ (which may itself have a solder tag) for receiving a terminal nut W₄ as shown in Figure 17.

It has been found from comprehensive tests that the improved volume control according to the invention is not only capable of withstanding normal tropical tests but can in fact withstand a temperature of 100° C. at 100% relative humidity for prolonged periods without any moisture penetrating the casing. It will also withstand continuous immersion in water for substantial periods without leakage into the casing.

Moreover, the construction of Figures 9 to 15 has a minimum of parts which are so arranged as to facilitate midget construction. Thus, for example, with this construction a tropic-proof

volume control having the characteristics normally required for wireless receivers may have a casing less than three-quarters of an inch in diameter and less than half an inch long. A further advantage of the construction, in addition to the very great reduction in size as compared with normal volume controls, is the improved heat dissipation obtained by the use of the metal casing as the main mechanical supporting structure.

It will be understood that the constructions above described are given by way of example only and that details may be made, within the scope of the invention, to suit the form and use of the resistor. Thus, for example, whilst the invention has been described as applied to a volume control of the circular type with a flat strip composition element, the resistor body may be of any other convenient shape and the element may be disposed in any other convenient manner, for example edgewise, and may consist of a conducting composition or may be wire-wound. It is also to be understood that where practicable any suitable materials other than those specifically mentioned may be used.

What we claim as our invention and desire to secure by Letters Patent is:

1. A variable electrical resistor comprising a cup-like aluminium casing open at one end and having an apertured end wall at the other end, an axially bored and externally screwthreaded bearing boss extending through said aperture, an insulating body secured to the boss within the casing, a rotary adjusting spindle within the bearing boss and extending through the insulating body into the casing, an annular groove, for containing sealing oil or grease, formed in the part of the spindle lying within the bearing, two supplementary annular grooves formed in the spindle on opposite sides of said oil groove respectively, rings of resilient material located in the supplementary grooves and compressed between the spindle and the bearing bore, a clamping nut engaging the external screwthread of the bearing boss outside the casing, a strip-like resistor element carried by the insulating body, a moving contact carried by the spindle and bearing resiliently against the resistor element, a resilient washer arranged in a recess around the inside of the aperture through the end wall of the casing, an insulating disc interposed between the insulating body and said end wall of the casing, the rubber washer being compressed between the base of said recess and the insulating washer when the clamping nut is tightened to draw the insulating body towards the said casing end wall, a resilient sealing disc closing the said open end of the casing, a rigid backing disc of insulating material arranged against the inner face of said sealing disc, the rim at the open end of the casing being spun into a bead housing the edge portions of the sealing and backing discs with the edge of said rim pressed into the outer surface of the sealing disc without perforating the disc, thereby hermetically sealing the joint between the casing and the discs, three tubular rivets extending through apertures in the discs, and three electric leads extending respectively into the rivets and electrically connected to the moving contact operated by the spindle and to the two ends of the resistor element, the outermost flanges of the rivets being pressed into the outer surface of the sealing disc whilst the leads are soldered in the rivets whose bores are thus hermetically sealed.

2. A variable electrical resistor comprising a cup-like aluminium casing open at one end and having an apertured end wall at the other end, an axially bored and externally screwthreaded bearing boss formed integral with the casing and projecting axially from the said end wall thereof, a rotary adjusting spindle within the bearing boss and extending into the casing, an annular groove, for containing sealing oil or grease, formed in the part of the spindle lying within the bearing, two supplementary annular grooves formed in the spindle on opposite sides respectively of said oil groove, resilient rings located in said supplementary grooves and compressed between the spindle and the bearing bore, an insulating body carried at the inner end of the spindle within the casing, a metal end plate carried on the inner face of the said insulating body, a moving contact constituted by an integral tongue struck up from said end plate, a resilient sealing disc closing the open end of the casing, a rigid insulating backing disc arranged on the inner face of the sealing disc, the rim at the open end of the casing being spun into a bead housing the edges of the sealing and backing discs with the edge of said rim pressed into the outer surface of the sealing disc without perforating the disc, thereby hermetically sealing the joint between the casing and the sealing disc, a strip resistor element carried on the inner face of the backing disc, three tubular rivets extending through apertures in the discs, three electric leads extending into the tubular rivets respectively and soldered therein so as to seal the bores of the rivets whose outer flanges or heads are pressed into the outer surface of the sealing disc without perforating the disc, thereby hermetically sealing the joints between the rivets and the sealing disc, and two springy contacts secured by and electrically connected to one of said rivets whilst the other two rivets are electrically connected to the two ends of the resistor element respectively, the two springy contacts bearing resiliently against the metal end plate of the spindle whilst the moving contact operated by the spindle bears resiliently against the resistor element.

3. A variable electrical resistor comprising a metal casing open at one end and having an apertured end wall at the other end, an externally screwthreaded and axially bored bearing boss extending through the hole in said end wall, a rotary adjusting spindle extending through the bore of said boss, at least one grease retaining annular groove being formed between the spindle and the said boss whilst at least one supplementary annular groove is formed between the spindle and the boss, a radially compressible sealing washer in said supplementary groove, an insulating block carried by the bearing boss within the casing, a moving contact carried by the spindle within the casing, a resistance element carried by said block and engaged by said moving contact, an axially compressible resilient washer embracing said bearing boss and located in a recess formed in the end wall of the casing, a locking nut engaging said external thread on the bearing boss outside the end wall of the casing, said nut causing the said resilient washer to be axially compressed in said recess between the end wall of the casing and said insulating block whereby the compressible washer seals the joint between the insulating block and the end wall of the casing, a sealing disc of resilient moisture-resisting material closing the said open end of

the casing, a rigid insulating backing disc arranged against the inner surface of the sealing disc, the rim of the casing being spun into a bead forming a shoulder abutting said backing disc whilst the said rim is spun inwards and pressed inwards into the outer surface of the sealing disc without perforating the disc, thereby sealing the joint between the casing and the sealing disc, three axially bored rivets in alignment with apertures extending through the sealing and backing discs, three electric leads extending into the said rivets whose rims are bent over and pressed into the outer surface of the sealing disc thereby sealing the joints between the rivets and the sealing disc, means within the casing connecting two of said leads to opposite ends respectively of the resistance element, and means within the casing

5 connecting the third lead to said moving contact.
